Primary Examiner — Kelley Donnelly(74) *Attorney, Agent, or Firm* — Keating & Bennett, LLP(57) **CLAIM**

The ornamental design for a foldable crate, as shown and described.

DESCRIPTION

FIG. 1 is a perspective view of a foldable crate according to my new design;

FIG. 2 is a side elevation view thereof;

FIG. 3 is a front elevation view thereof;

FIG. 4 is top plan view thereof; and,

FIG. 5 is a bottom plan view thereof.

The broken lines illustrated in FIGS. 1-5 are for the purpose of illustrating the environment of the design only and form no part of the claimed design.
